DESIGN FOR A DROP BOW COMPASS

Floyd G. Eubanks, Pasadena, Calif., assignor of forty-seven and one-half per cent to Francis E. Vaughan, Pasadena, Calif., and five per cent to Robert M. McManigal, Compton, Calif.

Application February 18, 1942, Serial No. 105,880

Term of patent 14 years

To all whom it may concern:

Be it known that I, Floyd G. Eubanks, a citizen of the United States, residing at Pasadena, in the county of Los Angeles and State of California, have invented a new, original, and ornamental Design for a Drop Bow Compass, of which the following is a specification, reference being had to the accompanying drawing, forming part thereof.

Figure 1 is a perspective view of a drop bow compass showing my new design.

Figure 2 is a front elevational view thereof; and

Figure 3 is a side elevational view thereof.

I claim:

The ornamental design for a drop bow compass, as shown.

FLOYD G. EUBANKS.
